ILLINOIS.

PRESSURE STILL.

Application filed January 17, 1921. Serial No. 437,662.

To all whom it may concern:

Be it known that we, JOHN E. BELL and EDWARD W. ISOM, citizens of the United States, residing, respectively, at Brooklyn, county of Kings, and State of New York, and Winnetka, county of Cook, and State of Illinois, have invented certain new and useful Improvements in Pressure Stills, of which the following is a specification.

10 The pressure stills to which our invention relate are designed to crack petroleum, gas oil and other heavy hydrocarbons and to convert them as far as possible into lighter hydrocarbons such as those constituting the 15 fraction known on the market as gasoline. In the operation of cracking such heavy hydrocarbons they are heated up to very high temperatures, commonly under high pressure, with the result that the heavier oils, 20 or a portion thereof, are broken down forming lighter oils which are vaporized and driven off. The vapors are condensed and submitted to further treatment to form the commercial product. In the formation of 25 the lighter oils carbon is freed or deposited in considerable quantity remaining behind in the heavy oil and tar in the still and on the heat absorbing surfaces of the latter with which the oil is in contact. The carbon and 30 heavy tar are very poor conductors of heat and when deposited upon the heating surfaces of the still which are exposed to the heating gases insulate the surfaces from the protection afforded by the oil so that the 35 heating surfaces are apt to become over-heated, the temperature of the metal surface increasing over the temperature of the oil to an extent dependent upon the thickness of the carbon deposit and the amount of heat 40 externally delivered to the heating surface from the furnace. As a consequence unless stills are frequently shut down for cleaning or the temperature of the furnace reduced below that which is most efficient, it is difficult 45 to maintain the stills in operation for a sufficient length of time to make such operation commercially practical. There is also considerable hazard to life and property because of the possible bursting of the 50 over-heated portions of the still, which is increased because of the pressure usually maintained in such stills which may be as much as one hundred pounds per square inch or more.

The surfaces of the still most exposed to

the heat of the furnace are of course most apt 55 to suffer, and in the case of a tubular still, to which our invention more particularly relates, the tubes which receive the greatest amount of heat from the furnace by reason 60 of their location, suffer the most. It is one 65 of the objects of our invention to provide an improved apparatus for cracking oil in which the heating tubes exposed to the products of combustion from the firebox at the highest temperatures contain oil which is 70 substantially free from carbon and tar, the oil as it accumulates tar and carbon and loses its content of crackable hydrocarbons flowing successively through heating tubes exposed to products of combustion from the 75 furnace at successively lower temperatures, thus enabling the still to be operated for a greater length of time between cleanings than is possible with the construction here- 80 fore known.

With this object in view we provide a tank body or drum containing the main body of oil to be cracked and connected as usual to a condenser in which the vapors constituting the desired fraction are condensed. The 85 drum is provided with transverse partitions of any desired number which separate the oil contained in the still into different bodies, and the oil to be cracked is fed to the first compartment and overflows from the first 90 compartment to the second and from the second to the third, and so on, being subjected to the cracking operation in each compartment so that it is, step by step, deprived of portions of the hydrocarbons which yield 95 to the cracking operation and increases step by step in the proportion of carbon and tar contained. The respective compartments are provided with heating tubes so connected thereto that the oil in each compartment 100 circulates through the heating tubes which appertain thereto and back to the compartment, the sets of heating tubes being arranged successively in the flues of the furnace so that those appertaining to the compartment first receiving the flow of oil are subjected to the highest temperature and succeeding sets of tubes are subjected to progressively decreasing temperatures.

In order that the vapors of the desired 105 composition may be developed approximately in equal quantities in the several compartments and the temperature of the oil itself

2
maintained, the number or total length of heating tubes is increased successively from the first to the last compartment. This arrangement also provides a large extent of surface on which carbon can be deposited in the coolest part of the still where it is least likely to be baked to a hard crust.

10 The circulation of the oil from the drum or the compartments thereof through the heating tubes and back to the drum may be caused or assisted by pumps or other mechanical means, or convective action due to the effect of heating and generation of vapors and fixed gases may be depended on 15 for this purpose, either method of circulation being within our invention in its broader aspect, and the invention is correspondingly broadly defined in certain of the following claims; in a companion application Serial No. 459,555, filed April 8, 1921, we have set forth and specifically claim such a construction in which forced circulation is provided, but in the present instance we have set forth and in the more 20 specific claims covered a construction in which natural circulation or convective action are relied upon.

25 In the accompanying drawings we have shown and in the following specification described in detail a preferred form of the apparatus of the invention. It is to be understood, however, that the specific disclosure is for the purpose of exemplification only and that the scope of the invention is 30 defined in the following claims in which we have endeavored to distinguish it from the prior art so far as known to us without, however, relinquishing or abandoning any portion or feature thereof.

35 In the drawings each part is identified by the same reference character wherever it appears in the several views.

40 Fig. 1 is a vertical longitudinal section of a preferred form of still embodying our invention on the broken line 1—1 of Fig. 2 parts being shown in elevation; Fig. 2 a 45 transverse vertical section of the same upon the line 2—2 of Fig. 1; and Fig. 3 a horizontal section upon the broken line 3—3 50 of Fig. 1.

45 The still drum 4 in the preferred form of the invention illustrated is supported upon I-beams 5 upon the furnace structure 6. The latter comprises a fire-box 7 which 55 may be of any known or approved construction and a series of vertical flues 8, 9, 10, 11, the first of which is connected at its lower end to the fire-box and at its upper end to the second flue, the latter being 60 connected to the third flue at its bottom and the third flue 10 being connected at its top to the last flue 11 which at its lower end is connected to the stack flue 12. Drum 4 is divided into a series of compartments 65 corresponding to flues 8 to 11 by partitions

13 and a battery of heating tubes is connected to each compartment and depends into the corresponding heating flue directly beneath the same so that the oil in each compartment is separately heated. In addition to the openings between the heating flues described above additional openings 14 and 15 controlled by dampers 16 and 17 may be provided in the walls between said flues as found desirable to further regulate 70 and control the heat distribution among the several heating flues.

75 In order to avoid exposing the first group or battery of heating tubes in the flue 8 to an excessive temperature from the freshly formed products of combustion rising from the fire-box we provide means for diluting the highly heated gases with any desired amount of waste gases taken from the lower end of the last flue 11 near the exit to the 80 stack, which gases have been considerably cooled by the passage through the heating flues in contact with the oil heating tubes, but still retain some available heat. For this purpose we have shown a passage or 85 conduit 18 connecting the bottom of flue 11 with a space 19 immediately behind bridge wall 20, the passage or conduit being provided with a venturi or other known forcing device. By returning a proportion of 90 the spent gases not only is the heat of the freshly formed products of combustion tempered but economy in fuel is accomplished by reason of the further utilization 95 of the available heat remaining in the returned gases and the increased volume or mass of gases brought into contact with the heating tubes in a given time.

100 Each of the compartments of the drum is provided with three complete heating units each of which comprises an out-flow header 21 and an inflow header 22 both connected into the bottom of the particular compartment of the drum with which they are associated and sets of inclined heating tubes 23 and 24, the tubes of the former set being connected to the outlet header 21 and inclining upwardly therefrom and the tubes of set 24 being connected to the inlet header 22 and extending downwardly 105 therefrom, corresponding tubes of the respective sets being connected together at the opposite side of the furnace from said headers by unions 25 (see Fig. 3). In 110 order to facilitate cleaning and repair the headers and unions are arranged beyond the heating chamber as shown in Fig. 2 and formed with plugged hand holes 26 and 27 in alignment with the respective tubes for 115 access to the latter. In operation the relatively cool oil in the compartments flows downwardly through the outlet headers 21 into the pipes 23 and thence by unions into the pipes 24 and inlet headers 22, the heating of the oil in the upwardly inclined pipes 120 125 130

23 and 24, and the development of gases and vapors therein causing a circulation of the oil upward through said pipes and headers 22 and consequently downward through 5 header 21. In order to provide for drainage and the withdrawal of tarry matter formed during the distillation and cracking of the oil the lower ends of headers 21 are connected into a manifold 28 and may be 10 drained through the outlet elbow 29. The lower ends of the headers in the last compartment are connected to the manifold 33 and outlet 34 to the tar draw off line, and if the still is operated continuously tar of 15 predetermined density may be continuously drawn off through this line.

As the products of combustion decline in temperature during their progress through the heating flues from the firebox to the 20 stack the absorption of heat by the oil in successive compartments would correspondingly decline were no provisions made to the contrary. As it is desirable that the cracking effect be as nearly uniform as practicable throughout the several compartments we offset or compensate for the decline in 25 temperature of the products of combustion as they progress along the heating flues by increasing the number of heating tubes in 30 the units in the successive vertical headers. In the specific apparatus shown the heating units identified with the first compartment of the drum and located in the first heating flue 8 have four tubes to the set, those in 35 the second heating flue have eight tubes to the set, those in the third heating flue have twelve tubes to the set, and so on. The surface for deposition of carbon and tar also thus increases with the content thereof in 40 the oil.

The drum is shown as provided with the usual reflux tower 32' from which the vapors escape through vapor-line 33' and which may receive oil to be treated through inlet 45 pipe 34'. The tower is located over the first compartment so that condensate flowing therefrom is returned to the latter. The drum is provided with an inlet pipe 35 leading into the first compartment and whether 50 oil be supplied through inlet 34' or inlet 35 it flows immediately into the initial compartment. The partitions 13 do not completely shut off the compartments from each other but extend a short distance above the 55 level at which the oil is to be maintained, the vapor space being open throughout the drum. The second, third and fourth compartments receive their respective charges through over-flow pipes 36, 37 and 38 opening through the respective partitions. Bells 39 over the over-flow pipes extend a proper distance below the top of the latter to retain the scum and froth on the surface of the oil in the respective compartments and pre-

vent it transferring into the succeeding compartments. 65

The fresh oil is received in the first compartment and is partially cracked therein, the vapors given off as well as the vapors from the other compartments passing into 70 the reflux tower which condenses and returns the fractions which are insufficiently cracked to the first compartment. As fresh oil is fed in a certain amount of the oil from the first compartment which has been deprived of a portion, at least, of its more readily cracked component and contains some tar and carbon continuously overflows into the second compartment where a further portion of its components is cracked 75 and vaporized, a portion of what remains being continuously fed to the third compartment, and so on, the oil in successive compartments containing less and less material which responds to the cracking operation 80 and more and more heavier material. The oil heating tubes connected to the first compartment and arranged in the first heating flue are subjected to the highest temperature of the products of combustion as heretofore pointed out, but this does not result in an 85 excessive deposit of carbon or separation of fixed gases and tarry matter because the oil in the first compartment and circulating through such tubes contains the maximum 90 amount of components which will easily crack without forming free carbon. The oil in the second compartment contains a smaller percentage of crackable components 95 than that in the first compartment but the deposition of carbon and release of fixed gas is not excessive because the lighter molecules are still being cracked without forming carbon to any great extent. The oil in the third compartment containing less crackable 100 hydrocarbon and more tarry matter and the like is subjected to a lower heating temperature than the oil in the second compartment, and so on. At the same time by reason of 105 the greater exposure of heating surface in successive compartments and flues the cracking effected in the respective compartments is more or less equalized, and the surface for depositing carbon is increased in the cooler portion of the still. 110

As heretofore pointed out, the tubes exposed to the highest temperature are protected from over-heating and burning because they contain constantly moving streams of oil capable of absorbing large quantities of heat because of their content of crackable components and which deposit little or no carbon upon the interior of said tubes so that the oil is directly in contact with the inner walls of the latter and rapidly absorbs heat therefrom, maintaining the walls relatively cool or below the burning temperature. 115 120 125

We claim:

1. In a still, a drum, partitions in the drum dividing it into a series of communicating compartments, means for supplying oil to the first of said series of compartments and permitting it to flow successively to the other compartments, means for leading off the vapors developed in the respective compartments, a furnace having an elongated heating flue, a corresponding series of separate heating coils arranged along the length of the heating flue and connected to the respective compartments of the drum for heating the oil therein where-by the oil is subjected to successively decreasing temperatures.

2. In a still, a drum, partitions therein dividing the drum into a series of communicating compartments, means for feeding oil to be cracked to the first of said series of compartments and permitting it to flow successively into the other compartments, a furnace having a heating flue, a corresponding series of separate heating coils arranged in said flue at successively increasing distances from the fire box and connecting respectively to the successive compartments of the drum to heat the oil therein, the coil connected to the first compartment being arranged to receive the first contact of the products of combustion of the furnace.

3. In an oil still, a drum to receive the oil to be cracked, partitions in the drum dividing it into a series of communicating compartments, means for feeding oil into the first of said series of compartments, and permitting it to flow successively into the other compartments, a furnace having an elongated heating flue, a corresponding series of separate heating coils connected respectively to the successive compartments of the drum and located in the heating flue, the coils being arranged in the heating flue successively to receive the heating gases in the same order in which the compartments with which they are connected are arranged in the drum.

4. In an oil still, a drum to receive the oil to be cracked, partitions dividing the drum into a series of compartments communicating both below and above the normal liquid level, means for feeding oil into the first of said series of compartments, a reflux condenser communicating with the vapor space above the several compartments and arranged to drain into the first of said series of compartments, means for feeding oil into the said first of the series of compartments, a furnace having an elongated heating flue, a corresponding series of separate heating coils connected to the respective compartments of the drum and located at progressively increasing distances from the fire-box in the heating flue, the coils of the said first compartment being ar-

ranged adjacent to the fire-box to be first impinged upon by the gases from the fire-box.

5. In an oil still, a drum to receive the oil to be cracked, partitions in the drum dividing it into a series of communicating compartments, means for feeding oil into the first of said series of compartments, and permitting it to flow successively into the other compartments, a furnace having an elongated heating flue, a corresponding series of separate heating coils connected to the respective compartments of the drum and located in the heating flue, the coils being arranged in the latter to be impinged upon by the heating gases from the furnace in the same order as the compartments with which they are connected receive the oil, the successive heating coils being of increasing heat absorptive surface to offset the decline in temperature of the heating gases along the heating flue.

6. In an oil still, a drum to receive the oil to be cracked, a series of transverse partitions dividing the drum into compartments, separate heating means for the oil in each compartment, means for introducing oil at one end of the drum and withdrawing residue from the other, an overflow pipe from each compartment to the next in the series, the inlet end of each overflow pipe being materially higher than the outlet end thereof.

7. In an oil still, a drum to receive the oil to be cracked, partitions in the drum dividing it into a plurality of communicating compartments, a furnace having a heating flue extending substantially longitudinally of the drum, a series of independent pipe coils connected with the respective compartments and arranged at successively greater distances from the firebox of the furnace within a heating flue thereof, the heating surfaces of the respective coils increasing with their respective distances from the firebox.

8. In an oil still, an elongated drum, means for feeding oil into one end thereof and drawing off residue from the other end thereof, means for condensing a portion of the vapors formed and returning the condensate to the feed end of the drum, a furnace beneath the drum having its fire box adjacent the feed end and its outlet adjacent the draw-off end of the drum, means for transferring heat from the products of combustion in the furnace to the contents of the drum at successive points longitudinally of the latter.

9. In an oil still, an elongated drum, means for feeding oil into one end thereof and drawing off residue from the other end thereof, means for partially separating the oil in the drum into a plurality of bodies, provisions permitting the flow of oil from

one body to the next past the last said means, the upper portion of the drum providing an uninterrupted passage for vapors from end to end thereof, means for leading 5 off the vapors formed, a furnace beneath the drum having heating passages extending substantially the length of the latter, a fire box communicating with the passages adjacent the feed end of the drum and an 10 outlet from the passages adjacent the draw-off end of the drum, and heating coils connected to the drum at intervals along the length thereof and extending into the heating passages of the furnace.

15 10. In an oil still, an elongated drum, means for feeding oil into one end thereof and drawing off residue from the other end thereof, a reflux tower arranged to communicate with the feed end of the drum, a 20 series of partitions dividing the lower portion of the drum into a longitudinal series of compartments, the upper portion of the drum being open from end to end for permitting the passage of vapors along the 25 same, tubes extending through the respective partitions, the ends thereof toward the feeding means being at a higher level than the ends toward the draw-off end of the drum, a furnace comprising heating passages beneath the drum, a fire box communicating with the passages adjacent the feeding end of the drum and an outlet from said passages adjacent the draw-off end of the drum, and circulating heating coils connected to the 30 respective compartments and extending into the heating passages of the furnace.

11. In an oil still, an elongated drum, means for feeding oil into one end thereof and drawing-off residue from the other end 40 thereof, partitions dividing the lower part of the drum into compartments but leaving the upper portion of the drum uninterrupted for the passage of vapors along the same, means for drawing off the vapors formed, a 45 furnace beneath the drum having a series of connected heating flues arranged beneath and corresponding to the respective compartments of the drum, a fire box connected to said flues adjacent the feed end of the 50 drum, an exhaust flue connected to said heating flues at the draw-off end of the drum, and a series of heating coils extending from the respective compartments into the flues beneath the same, the heat absorbing 55 surfaces of the coils increasing successively from the feed to the draw-off end of the drum.

12. In an oil still, an elongated drum, means for feeding oil into one end thereof and drawing off residue from the other end thereof, partitions dividing the lower part of the drum into compartments but leaving the upper portion of the drum uninterrupted for the passage of vapors along the same, 60 means for drawing off the vapors formed, a

furnace beneath the drum having a series of connected heating flues arranged beneath and corresponding to the respective compartments of the drum, a fire box connected to said flues adjacent the feeding end of the 70 drum, an exhaust flue connected to said heating flues at the draw-off end of the drum, and a series of heating coils extending from the respective compartments into the flues beneath the same, each coil comprising 75 a pair of headers at one side of the heating flues and series of inclined pipes extending across the flues and connected to said headers.

13. In an oil still, a furnace having a 80 heating flue, a drum adapted to contain a charge of oil, a reflux tower communicating with the drum, heating means arranged in the heating flue and connections for circulating oil from and to the drum there-through, a separate heating means communicating with the drum arranged in the heating flue between the first mentioned heating means and the furnace, connections for introducing fresh oil into the reflux tower, and means for initially circulating the fresh oil and admixed reflux through the last mentioned separate heating means.

14. In an oil still, a drum, partitions 95 therein dividing the drum into compartments, there being openings in the partitions through which the compartments communicate, a furnace having a heating flue, heating units in the flue connected to the respective compartments, means for supplying oil to be treated to one of said compartments and causing it to flow successively to the other compartments and a reflux tower adapted to receive the vapors from the various compartments and adapted to discharge into the compartment provided with means for supplying oil thereto, the heating unit connected to said last mentioned compartment being arranged in the heating flue nearest the 100 furnace.

15. In an oil still, a drum, a series of transverse partitions dividing the drum into successive compartments, there being communication between said compartments, means for supplying oil to the compartment at one end of said drum, means for withdrawing residue from the compartment at the other end of said drum, a reflux tower arranged to discharge into the compartment at the first said end of the drum and adapted to receive the vapors from all of said compartments, a furnace having a heating flue and heating units connected to the several compartments respectively and extending into said heating flue, the heating unit connected to the compartment at the first said end of the drum being arranged in the heating flue nearest the furnace.

16. In an oil still, a drum, transverse partitions in the drum dividing the same into

successive communicating compartments, means for feeding oil into the first of said compartments at one end of the drum, a furnace having a fire box and a series of heating flues corresponding in number and position to the compartments of the heating drum, the fire-box communicating with the flue corresponding to the first said compartment, heating units located in the respective flues and connected to the respective compartments, supplemental passages connecting said flues and valves arranged in said passages for controlling the passage of products of combustion therethrough. 10
